CONTROL SYSTEMS FOR POWER DEVICES

Robert G. Quick, Richmond, Va., assignor to Flight Research, Incorporated, a corporation of Virginia

Application May 2, 1957, Serial No. 656,536

4 Claims. (Cl. 317—148.5)

This invention relates to power controlling apparatus, and, more particularly, to apparatus including a meter movement relay for controlling the application of power.

One of the most sensitive devices for control purposes is a meter movement relay, preferably of the well-known D'Arsonval type. This type of relay, despite the advantage of its high sensitivity, also has very low torque output, so that, when it is used in power applications, some means for protecting the contacts of the relay must be found. Particularly when the apparatus is subject to vibration, the resultant separations of the contacts of the meter movement relay cause arcs between those contacts which eventually build up into carbon deposits which finally prevent contact closure of the relay. Also, during the closing movement of the relay contacts, the stray capacity of the switch elements and the associated wiring causes transient currents to flow through the switch contacts, which currents frequently result in the contacts being welded together. Since the restorer spring must have a low torque, the welding results in the contacts remaining closed and errors in indication result. Moreover, vibration of the mounting means for the relay causes chattering of the contacts so as to result in improper operation of the device being controlled by the relay.

The prior art has proposed solutions to these problems, one of which is to provide the stationary contacts of the meter movement relay with permanent magnets and to provide the pointer, or movable contact, of the relay with an iron tip. When the contacts engage, magnetic attraction holds them engaged, to supplement the torque imposed on the pointer by the current flowing through the coil of the meter movement. While this proposal does result in more perfect engagement of the contacts, some mechanical device is necessary to interrupt the contacts, because the torque caused by current through the metered coil will not ordinarily be sufficient to separate the contacts against the permanent magnet attraction. This proposal, consequently, is not completely satisfactory, particularly for high speed operation.

A second earlier suggested way to improve the contact engagement of meter movement relays is to provide a supplemental winding on the relay which is normally open but which is provided with current when the contacts close. The supplemental winding provides an increased torque which tends to maintain the contacts closed. While better engagement and protection against chattering is provided by this proposal, the proposal necessitates an additional circuit for interruption of the supplemental winding circuit when the meter movement contacts are to be opened. Further, the required current through the contacts of the relay in order to control the supplemental winding causes deterioration of the contacts and limited life for the relay.

While the apparatus of the present invention has broad utility in any control system for a power device, it was especially designed to control automatically the aperture setting of a motion picture camera. For such use, a con-

trol had to be designed which would be responsive to a current of no more than 2.5 microamperes. For an illustration, 1,000 ohms coil of a D'Arsonval relay, a current of this magnitude would provide approximately 6 thousandths of a microwatt of power. It is evident that the torque available to close the contacts of the D'Arsonval movement is extremely small, so that some type of apparatus for maintaining the contacts closed after closure, or for compensating for chattering, had to be found in order to provide proper operation of the motor which controlled the aperture setting of the camera.

It was found that, if the contacts of the D'Arsonval relay were allowed to separate but their separations compensated for by use of a time delay circuit, the necessity for such devices in the prior art as referred to above, was avoided. It was also found that a current-limiting resistor in series with the contacts would prevent high transient currents through the contacts and improve their useful life. However, the problem of how to control a motor, which is a relatively high power device as compared with the power available from the D'Arsonval movement, still remained. The present invention utilizes a switching device, such as a transistor, between the D'Arsonval control system and the motor system, with the output of the switching device operable to control a relay which operates the power device.

It has been found that the combination of elements referred to above permits satisfactory and positive operation of a power device for a long period of time without complicated or expensive circuitry and with relatively small volume required for the elements of the control apparatus.

The apparatus of the invention, generally speaking, includes a meter movement relay with at least a movable contact and a fixed contact, a control circuit for the relay, a power relay for controlling the power device, a source of potential connected to the power relay when a switching device is operated, and a circuit including an R-C time delay circuit and the contacts of the meter movement connected to the switching device to control its operation. As indicated above, a current-limiting resistor is also connected in series with the contacts of the meter movement relay, and the capacitor is connected across the series combination of the contacts and this resistor.

The apparatus of the invention will now be more fully described in conjunction with a preferred embodiment thereof, as shown in the accompanying drawing.

In the drawing,

50 Fig. 1 is a schematic diagram of the complete control system of a preferred embodiment of the invention; and

Fig. 2 is a simplified schematic of the apparatus of Fig. 1 showing a portion thereof, so as to permit a more ready explanation of the operation of the apparatus.

55 Referring first to Fig. 1, the power controlling apparatus is itself controlled by a control circuit 1 which provides current from a source of potential indicated as battery 2, to a meter movement relay 3, which is preferably of the D'Arsonval type. The meter movement relay includes a coil 4 connected to the output of control circuit 1, and a movable contact 5 which selectively engages stationary contacts 6 and 7. The meter movement relay is intended to control a pair of power relays 8 and 9 whose contact sets are connected to a power circuit 10 containing the device to be controlled. For instance, the power circuit 10 may include a motor for performing any appropriate function, such as controlling the aperture setting of a motion picture camera. As an illustration of practical use of the power relays to control a power device, the relays may be connected to be inoperable to drive the motor when both are unenergized, and one relay when energized may close a circuit

to drive the motor in one direction and the other relay when energized may close another circuit to drive the motor in the reverse direction.

Power relays 8 and 9 are in the output circuits of transistors 11 and 12, one side of the coils of power relays 8 and 9 being connected to the collector elements of the respective transistors, and the other sides of the coils being connected to the negative side of battery 2 by conductor 13. The emitters of the transistors 11 and 12 are connected by lead 14 to the positive side of battery 2. Therefore, when sufficient current is flowing through either of the emitter-collector circuits of the transistors, the associated power relay is energized.

The input circuit of transistor 11, the control circuit therefor, includes movable contact 5 and stationary contact 6 of the meter movement relay 3. The stationary contact is connected through a resistor 15 to lead 16 which is connected to the base of transistor 11. Lead 16 is connected through the series combination of a stabilizing resistor 17 and a thermistor 18 (whose purpose will subsequently be explained) to the emitter of the transistor.

Similarly, stationary contact 7, in the input circuit of transistor 12, is connected through resistor 19 and lead 20 to the base of the transistor, while lead 20 is connected through stabilizing resistor 21 and thermistor 22 to the emitter of transistor 12.

A pair of capacitors 23 and 24 are connected across stationary contacts 6 and 7, with their common lead being connected to lead 13, and hence to the negative side of battery 2.

A current-limiting resistor 25 is connected between the movable contact 5 of the meter movement relay and lead 13. This resistor is preferably placed immediately adjacent the contacts so as to prevent the stray capacitance between them from furnishing an unlimited surge current through them on closure.

In order that the operation of the apparatus of Fig. 1 may be more easily understood, reference is now made to Fig. 2 which is a schematic of substantially one-half of the control system of Fig. 1. That is, Fig. 2 shows the circuit of transistor 11 and its power relay 8, together with the meter movement relay contacts and the rest of the control circuit for that transistor. When the contact 5 is out of engagement with contact 6 of the apparatus of Fig. 2, the connections and the transistor selected are such that there is no appreciable current flow in the emitter-collector circuit of the transistor, so that power relay 8 is not energized.

An important feature of the invention is that the entire potential of battery 2, plate potential, is connected across the meter relay contacts before they engage. This is necessary in order that the resistance of oxide and dust films may be broken down, despite the relatively low torque supplied the pointer of the relay by the low control current, in order to provide a low resistance circuit in the input of the transistor switching device.

When movable contact 5 moves over to engage contact 6, a circuit to the negative side of battery 2 is completed, and the transistor is cut-on, to furnish sufficient current through the power relay to energize it. The time interval after closure of the switch contacts before the transistor is cut-on depends upon the magnitude of the capacitor 23 and resistor 25, which latter functions to discharge capacitor 23. During the closure operation and subsequent operation of the apparatus, resistor 25 limits the current which can flow through contacts 5 and 6 to a value such that the life of the contacts is increased as far as possible.

When vibration or decrease of current through the coil 4 of the meter movement relay causes contacts 5 and 6 to separate, capacitor 23 and resistor 15 form an R-C time delay circuit which keeps the transistor cut-on for a time period after opening of the contacts determined by the values of the respective elements. The values are

preferably chosen so that the time constant of the circuit is substantially longer than the longest period of vibration to be expected with the apparatus, so that contacts 5 and 6 will close again before the R-C circuit 23 and 15 permits the transistor 11 to cut-off and de-energize relay 8.

Thermistor 18 is provided to insure that the quiescent current of the transistor will be negligible, that is, that the current through the emitter-collector circuit when the switch contacts are open in static condition will be nil.

It will be evident from the above explanation of the operation of Fig. 2 how the apparatus of Fig. 1 operates. When contacts 5 and 6 close, transistor 11 is cut-on to energize power relay 8, while, when contacts 5 and 7 close, transistor 12 is cut-on to energize power relay 9. The appropriate connections are made in power circuit 10 to influence the power device in any desired manner. As with capacitor 23 and resistor 15, capacitor 24 and resistor 19 form an R-C time delay circuit for transistor 12 to keep it energized for a selected time period after opening of contacts 5 and 7. Thermistor 22 and resistor 21 are connected in the circuit and to the battery in such fashion as to maintain the transistor 12 cut-off until the contacts 5 and 7 close.

It will be noted that the R-C time delay circuit operative to keep each transistor on for a time period after opening of the associated switch contacts is in the input circuit of the transistor. Since the low resistance in the output circuit would require a higher value of capacity for the same time constant, this placing of the time delay circuit is much superior to having it in the output circuit.

In practical operation of the apparatus of the invention to control the aperture setting of a camera, for instance, the apparatus disclosed may function for several months to provide continuous control under the influence of, for example, of a photocell, with only the power supplied from simple dry batteries. The power drain from such a source to the control apparatus would be minimum, because the transistors would consume power only when they were turned on to effect their control function.

It will be evident that a different type of switching device than the transistors shown could be employed. For instance, a vacuum tube could be employed and the circuit redesigned to cause it to operate in similar fashion to the transistor. However, particularly for applications where size and weight of components are important, as well as power considerations, since filament power drain is not involved, the transistor will be found to be immensely superior to the vacuum tube. Especially for a system for control of the aperture setting of a motion picture camera, and even more importantly where such apparatus is designed to be carried by hand with the camera, the transistor is the only practicable switching device presently known for this purpose. Either a transistor or a vacuum tube would be superior to any other type of switching device however, because the amplification they provide permits low current through the contacts.

It will be evident that many different types of power devices could be controlled by an apparatus of the type described herein. It will also be evident that many minor changes could be made in the circuitry of the apparatus without departure from the scope of the invention. The invention is therefore not to be considered to be considered to be limited to the embodiment disclosed in the application, but rather only by the scope of the appended claims.

I claim:

1. Apparatus for controlling a power device comprising a meter movement relay having a movable contact and at least one fixed contact, a control circuit for the meter movement relay operable to supply sufficient current through the coil of the meter movement to close the fixed and movable contacts, a transistor, a source of D.-C. potential, a power relay, the coil of the power relay

being connected between a first one of the transistor elements and one side of the source of potential, a second of the transistor elements being connected to the other side of the source of potential, a current-limiting resistor and a second resistor, the series combination of the current-limiting and second resistors and said contacts being connected between the third transistor element and said one side of the source of potential, means including a resistance means connecting the second and third transistor elements together, said transistor being normally cut-off, and a capacitor connected across the series combination of said contacts and said current-limiting resistor operable with said second resistor to form an R-C time delay circuit, said contacts when closed being operable to cut-on said transistor to cause it to conduct sufficient current between said first and second elements to energize said power relay, said power relay being operable to control said power device, said R-C time delay circuit being operable to keep said transistor cut-on for a time period after said contacts open.

2. Apparatus as defined in claim 1 which said connecting means includes a thermistor.

3. Apparatus for controlling a power device comprising a meter movement relay having a movable contact and a pair of stationary contacts alternately engageable by the movable contact, a control circuit for the meter movement relay operable to supply sufficient current through the coil of the meter movement to cause the fixed contact to engage selectively one and the other of the fixed contacts, a pair of power relays, a source of D.-C. potential, a pair of transistors, each of the power relays being connected between one of the elements of a different one of the transistors and one side of the source of potential, a second element of each transistor

being connected to the other side of the source of potential, a current-limiting resistor connected between said movable contact and said one side of the source of potential, a pair of capacitors and a pair of resistors, one side of each of the capacitors being connected to a different one of the stationary contacts and the other sides of the capacitors being connected to said one side of the source of potential, one of said pair of resistors being connected between a third element of one of the transistors and one of the stationary contacts and the other resistor being connected between a third element of the other transistor and the other stationary contact, and means including a resistance means connecting the third and second elements of each transistor together operable to maintain the transistors cut-off, the movable contact and said one stationary contact being operable when engaged to turn said one transistor on and operate said one power relay and the movable contact and said other stationary contact being operable when engaged to turn said other transistor on and operate said other power relay, said pair of capacitors and said pair of resistors forming R-C time delay circuits operable to keep their associated transistors on for a period of time after the associated contacts open, said power relays being operable to control said power device.

4. Apparatus as defined in claim 3 in which said connecting means comprises a pair of thermistors, one in each transistor circuit.
